Inventor:

① Oliver A. Krasser.

UNITED STATES PATENT OFFICE.

OLIVER A. KRAEER, OF BARTLESVILLE, OKLAHOMA.

TUBING OIL SAVER.

Application filed December 13, 1921. Serial No. 522,394.

To all whom it may concern:

Be it known that I, OLIVER A. KRAEER, a citizen of the United States of America, residing at Bartlesville, in Washington County, State of Oklahoma, have invented a new and useful Improvement in Tubing Oil Savers.

This invention is for the purpose of saving the oil in the tubing of an oil well when it is necessary to pull the tubing to clean out the well, or for any other reason; and also to carry off such oil or any refuse in the tubing, when the same is pulled, and dispose of the same so that it will not interfere with the progress of the work.

When it is necessary to pull the tubing out of an oil well, the tubing is generally full of fluid. The tubing is raised until a connection between joints is reached, when the top joint is unscrewed from the lower. The fluid in the upper joint then commonly runs out on the ground or floor, wasting the oil, if the tubing is full of oil, and permitting the fluid to run over the derrick floor, greatly hampering the workmen in their work.

My invention consists of two half-cylindrical shaped sides; each side has a lock-arm and a hinge-arm; the hinge-arms are hinged on a hinge-bolt attached by means of a clamp or saddle to the gas pipe in the casing head. The hinge-bolt has an offset bend and a collar with a set screw at a convenient point on which the hinge arms rest. The top and bottom inside edges, where they fit around the tubing, and the inside edges of the sides, where they come together, are fitted with packing, leaving a circular hole in the center for the tubing. The sides are larger in diameter at the bottom than at the top, to allow for the bottom setting over the collar of the lower joint of tubing. One of the sides has a spout near the bottom for hose attachment. One of the lock-arms has a hook on the bottom in which is adjusted a lock-link with a handle, which is used to fasten the lock-arms and sides together when adjusted around the tubing. On the outside of the lock-arms is a wedge-boss to facilitate the locking of the sides together when adjusted around the tubing. When the oil saver is adjusted around the tubing, the lower part being adjusted around the

collar of the lower joint of tubing and the upper part around the upper joint, the packing fits closely together around the tubing at the top and bottom and comes together along the edges, making a cavity between the tubing and the sides of the oil saver, to take care of the fluid in the upper joint of tubing as it is being unscrewed, and when the upper joint of tubing is unscrewed the fluid runs from it down through the spout in the side of the oil saver and through the hose adjusted thereon back into the casing of the well or into a tank, or such other receptacle as may be provided therefor. To adjust the oil saver around the tubing the sides are forced together, the lock-link pushed up over the lock-arms and the tubing is then unscrewed by means of pipe tongs. When not in use the lock-link is drawn back from the lock-arms and the sides are thrown out of the way.

The hinge-bolt screws into a clamp or saddle attached to the gas pipe leading out of the casing-head. There is an offset bend in the hinge-bolt. By turning the hinge-bolt to the right or to the left in its screw-socket in the clamp or saddle the oil saver can be moved up to or away from the tubing or it can be opened up and moved back out of the way. I am aware that the idea of an oil saver is not new; but claim that the combination with the oil saver of the lock-arms, hinge-arms, and hinge-bolt with off-set bend, adjusted in a saddle or clamp on the gas pipe leading out of the casing-head is a patentable invention.

The combination herein described is shown in the accompanying drawings.

Figure 1 shows an inside view of the oil saver opened out to full length. Figure 2 is an outside view of the oil saver opened out to full length. Figure 3 shows the oil saver adjusted around the tubing.

a and *b* are the sides of the oil saver.

c and *d* are the lock arms.

e is a beveled boss on the lock arms.

f and *g* are the hinge arms.

h is a circular hole in one side of the oil saver with spout for hose attachment.

i is the hinge bolt with offset bend.

j is the packing in the top and bottom inside edges where they fit around the tubing.

and in the inside edges of the oil saver where they come in contact.

k shows the hose attached to the spout.

m shows the collar on the hinge bolt.

n shows a set screw in the collar *m*.

p shows the saddle on the pipe in the casing-head.

r shows the lock link with handle attached.

10 I claim as new and desire to secure by Letters Patent:

A tubing oil-saver having two semi-cylindrical sides; each side having a hinge-arm and a lock-arm; each lock-arm having a beveled boss on the outside; a lock-link with a handle at one end, the other end of the lock-link being adjusted in a hook on one of the lock-arms; the ends of the hinge-arms being hinged together and resting on a

collar, with a set screw on a hinge-bolt having an offset bend screwed into a clamp or saddle attached to the gas pipe in the casing-head; the sides of the oil saver where they come in contact on the inside edges, and the top and bottom inside edges where they come in contact with the tubing being lined with packing, leaving a cylindrical cavity between; one of the sides having a spout with an opening into the cavity of the oil-saver with hose attachment, substantially as described.

In testimony whereof, I have signed this specification in the presence of two subscribing witnesses, this 19th day of July, 1921.

OLIVER A. KRAEER.

Witnesses:

EVA VAN DEVENTER,

J. E. SANDERSON.
